(57) **CLAIM**

(21) Appl. No.: **29/151,353**

The ornamental design of a spray arch for vehicle washing machine, as shown and described.

(22) Filed: **Dec. 4, 2001**

DESCRIPTION

(51) LOC (7) Cl. **15-05**

FIG. 1 is a perspective view illustrating the spray arch for a vehicle washing machine of the present invention;

(52) U.S. Cl. **D32/4**

FIG. 2 is a right side view of the spray arch for the vehicle washing machine of the present invention;

(58) Field of Search D32/4, 25, 30;
D23/213, 223, 228; 239/8, 202, 366; 34/666;
15/312.1, 326, 419

FIG. 3 is a front view of the spray arch for a vehicle washing machine of the present invention;

(56) **References Cited**

FIG. 4 is a back view of the spray arch for a vehicle washing machine of the present invention;

U.S. PATENT DOCUMENTS

FIG. 5 is a left side view of the spray arch for a vehicle washing machine of the present invention;
